Des. 798

Albert Bosworth of Westfield, Mass. No. 798
Albert Bosworth and Timothy H. Loomis.
Letters Patent No. 798, Dated May 27th 1856.

The schedule referred to in these Letters Patent, and making part
of the same.

To all whom it may concern:

Be it known that I, Albert Bosworth of Westfield
in the County of Hampden and State of Massachusetts, have inven-
ted or produced a new and original design for a piano forte leg.
And I do hereby declare that the following is a full and complete
description of the same, reference being had to the accompanying
drawing, which represents the peculiar features of my design.

The base A, and Corona B, may be varied or
changed at pleasure, as they do not form a necessary part of the
ornamental design or figure herein specified.

The fluted column C, commencing at D, with
a deep carve cut represented at I, and terminating at E, above
the base forming a tapering flute, forms part of the design, and
the peculiar curve of the jutting points at E, E', E", & is another part
of the configuration, which is deemed essential to the completeness of
this design. I do not include herein any form of fluted piano forte
leg, which does not correspond substantially in the manner and form
of fluting, curving and pointing herein specified.

I am aware that legs for piano fortés have been

Des. 798

fluted from the top to the bottom of the central part of the column or leg. They have also been constructed in two or more parts, with one of those parts fluted and the other a parallel section projecting over such fluted portion with a variety of forms and devices, but I am not aware that they have been designed with the concave cut here represented or with the peculiar curve of the jutting points F; F; F. &c.

What I claim is the forward configuration of the central fluted column and the pendant or jutting device at F; F; F. The whole producing an ornamental design for a pianoforte leg.
